GRINDING MACHINE

Original Filed Feb. 3, 1926

UNITED STATES PATENT OFFICE

FRED M. KERN, OF DETROIT, MICHIGAN, ASSIGNOR, BY MESNE ASSIGNMENTS, TO CINCINNATI GRINDERS INCORPORATED, OF CINCINNATI, OHIO, A CORPORATION OF OHIO

GRINDING MACHINE

Application filed February 3, 1926, Serial No. 85,790. Renewed March 1, 1929.

This invention relates to grinding machines for grinding successive pieces of work to a uniform predetermined size, and more particularly to machines for grinding short cylindrical or shouldered work wherein the work is positioned for rotation and grinding between a rapidly rotated grinding wheel and a slowly rotated work regulating wheel.

One of the objects of the invention is to provide a machine of the above nature which is capable of a wide range of use. Another object is to provide a machine of the above nature which is thoroughly practical and efficient.

Another object is to provide a centerless grinding machine capable of accurately and rapidly grinding work which is not uniformly cylindrical throughout its length, and capable of convenient adjustment to meet the varying requirements of such grinding.

It is a further object of the invention to provide a precision grinding machine with an adjustable mechanism so that it may be easily adapted for grinding successive pieces of relatively short work to any predetermined size without removing and replacing any part of the mechanism.

It is a further object of the invention to provide a centerless grinding machine in which either the grinding wheel or the regulating wheel may be moved towards and away from the other wheel to grind successive work pieces to a substantially uniform predetermined size, and which is so constructed and arranged that the total travel of the movable wheel may be as large as possible for roughing cuts, or very small for finishing cuts.

It is a still further object of the invention to provide a mechanism, in a machine for grinding successive work pieces to a predetermined uniform size by periodically moving one of the wheels an invariable distance rapidly into approximate contact with the work, the work being then slowly ground, which may be adjusted to control the travel of the periodically moving wheel to obtain a desired depth of cut upon the work and at the same time always maintain the same general cyclic movement of the moving wheel relative to the work.

In one of the possible embodiments of the

invention I provide a grinding machine having an adjustable mechanism which may be set to obtain a relative movement of any desired invariable amount between the grinding wheel and the work to grind successive work pieces uniformly to a predetermined size. This mechanism may be embodied in any type of grinding machine, such as a machine for grinding cylindrical work in which the work is held on centers; but is particularly applicable to a centerless grinding machine in which a work piece is positioned between a rapidly rotated grinding wheel and a slowly rotated work regulating wheel which are arranged as in any of the well known types of centerless grinding machines. Preferably, the work is maintained in rotative contact with the regulating wheel and either the grinding wheel or the regulating wheel may be moved relatively to the other wheel to cause the grinding wheel to grind successive work pieces uniformly to any predetermined size as desired. My preferred practice is to mount the grinding wheel rotatively in an eccentric trunnion which may be turned to feed the wheel towards and from the work. The trunnion may be oscillated cyclically by means, for example, of a positively rotated cam which is operatively connected with the trunnion by a mechanism which may be adjusted to modify the effective action of the cam and thereby turn the trunnion through a greater or less distance. This may comprise an arm extending laterally from the trunnion which is moved by the cam through an intermediate pivoted lever and an adjustable member arranged to move the trunnion in response to the movement of any point on the lever.

The invention accordingly consists in the features of construction, combinations of elements, and arrangements of parts as will be exemplified in the structure to be hereinafter described and the scope of the application of which will be indicated in the following claims.

In the accompanying drawing in which is shown one of the various possible embodiments of this invention,

Figure 1 is a partial side elevational view, partly in section, of a centerless grinding

machine adapted for grinding short or shoul-
dered work;

Fig. 2 is an elevational view partly in sec-
tion of certain mechanisms embodied in the
5 machine shown in Fig. 1; and

Fig. 3 is a partial plan view of a section
through the grinding wheel spindle.

Similar reference characters refer to simi-
lar parts throughout the several views of
10 the drawing.

While the invention will be described by
reference to its application to a centerless
grinding machine, nevertheless it is not so
limited as will be understood readily by those
15 skilled in the art, and is equally applicable
to any precision grinding machine wherein
it is desirable to obtain a relative movement
between the grinding wheel and the work to
grind successive work pieces uniformly to
20 a predetermined size. The machine illus-
trated comprises a frame 10 having a hollow
cylindrical portion 11 within which a column
12 is mounted for vertical movement. The
column 12 is prevented from turning in the
25 portion 11 by a key 13 engaging a groove
14 in the column. A spindle 15 carrying a
regulating wheel 16 is mounted for rotation
in suitable bearings (not shown) within the
bearing casing 17 upon the support 18 inte-
30 gral with or suitably secured upon the top of
the column 12, and is rotated relatively slow-
ly from any suitable source of power, such as
a motor (not shown), transmitted through
the shaft 19 carrying a worm 20 which en-
35 gages a worm wheel 21 secured upon the
spindle 15.

An upwardly extending bracket 22, formed
as an integral part of the column 12, is pro-
40 vided with slide ways 23 for a slide 24 having
two horizontally extending arms 25 and 26
on each side of the machine. A work holding
member or blade 27 is adjustably mounted
upon the arm 25 by means of bolts 28 passing
45 through slots 29 in the blade. A bracket 30
is provided with a pair of tongues 31 engag-
ing slots 32 in the arms 26, and is adjustably
mounted thereon by means of bolts 33 passing
through slots 34 in the arms. A front work
50 holding member or blade 35 is adjustably
mounted in the bracket 30 by means of bolts
36 passing through slots 37 in the blade. In
the form of machine shown in the drawing
the work *w* is positioned upon the regulat-
55 ing wheel 16 and maintained in a proper
grinding position by the rear blade 27. The
rear and front blades 27 and 35 respectively
may be adjusted vertically simultaneously by
turning a shaft 38 mounted in the bracket 22
60 and carrying a pinion 39 engaging a rack
40 on the slide 24.

A water pan 41 is secured to the column 12
by means of bolts 42 passing from the column
into the support 18. The regulating wheel
65 16 and the bracket 22, as well as the water
pan 41, may be moved vertically by turning a

screw shaft 43, which is mounted, so as to pre-
vent longitudinal movement, in a bearing 44
in the column 12 and is arranged to engage a
threaded hole 45 in a boss 46 secured to or
integral with the frame 10. The screw shaft
70 43 may be turned by means of a hand wheel
(not shown) secured upon a shaft 47 carry-
ing a worm 48 which engages a worm wheel 49
mounted upon the screw shaft 43.

Referring now to the grinding wheel
mounting, I preferably mount the wheel on
a spindle carried in a hollow trunnion 55
which is mounted for oscillatory movement
in a bearing surface 56 in the frame 10.
Eccentrically carried in the trunnion are
80 bearings 57, shown as split tapered bearings,
which may be suitably constructed as is well
known in the art, and in which the grinding
wheel spindle 58 is mounted for rotation. A
grinding wheel 60 is suitably secured upon
85 one tapered end of the spindle 58 as by means
of a key 61 and a nut 62. A pulley 63 driven
in any suitable manner, as by means of a belt
64, may be secured at the other end of the
spindle 58 for rotating the same. 90

The character of the eccentric mounting of
the spindle 58 within the trunnion 55 is clearly
illustrated in Fig. 2. The center of the trun-
nion is indicated by the intersection of the
lines A and C, and the center of the spindle
58 is indicated by the intersection of lines
95 A and B. It will be apparent that as the
trunnion 55 is turned, the spindle 58 and the
grinding wheel 60 will be moved towards
and away from the regulating wheel 16 by
100 pivoting about a point located at the inter-
section of the lines A and C. 95

My preferred mechanism for turning the
trunnion 55 includes an arm 68 extending
105 rearwardly from the trunnion as an integral
part thereof and having a follower 69 adjust-
ably mounted within a slot 70 in the arm by
means of an adjusting screw 71. The fol-
lower 69 is held downwardly by means of
a weight 72 suspended from the end of the
110 arm 68 by a rod 73, and is thereby main-
tained in contact with the plane bearing
surface 74 on an arm or lever 75 which is
pivoted at one end to turn about a shaft 76
and is provided at its other end with a cam
follower 77 adapted to ride upon the periph-
115 eral surface of a cam 78 secured upon a
rotatably mounted shaft 79. The shaft 79
may be rotated in the direction indicated by
the arrow in Fig. 2 by means of a worm 80,
120 secured upon a shaft 81 and engaging a worm
wheel 82 secured upon the shaft 79. The
shaft 81 may be driven from any appropriate
source of power, and may be connected, for
example, with a rotatably driven shaft 83 by
125 means of a belt 84 passing over pulleys 85
and 86 mounted respectively on shafts 81 and
83.

The machine may be adjusted for grinding
work of any desired size by moving the regu- 130

lating wheel 16 up or down to an appropriate position by turning the hand wheel (not shown) secured upon the shaft 47 carrying the worm 48. The rear blade 27 and the front blade 35 are then moved vertically to an appropriate position between the wheels to properly position the work upon the lower wheel 16 by turning the shaft 38 and the worm 39 to raise the slide 24 an appropriate amount. The bolts 28 are then unloosened so that the work holding member 27 may be moved in a horizontal direction to a proper position. The front guide blade 35 may be moved in a horizontal direction to an appropriate position by unloosening the bolts 33 and sliding the bracket 30 along the slots 32 in the arms 26, and further horizontal adjustments may be obtained by unloosening the bolts 36 to permit movement of the blade 20 relative to the bracket.

Power is then supplied from any appropriate source to turn the shaft 19 and move the belts 64 and 84 to rotate, respectively, the regulating wheel 16 relatively slowly and the grinding wheel 60 rapidly in the directions indicated respectively by the arrows in Fig. 1, and to impart a continuous rotary movement to the shaft 79 and the cam 78. The action of the cam 78 causes the arm 75 to oscillate so as to move the follower 69 and the arm 68 up and down to turn the trunnion 55, and thereby cause the spindle 58 and the grinding wheel 60 to move towards and away from the regulating wheel 16 and the work 35 *w* which is supported between the two wheels.

It will be apparent that the grinding wheel 60 may be caused to move towards and away from the regulating wheel 16 through any predetermined invariable distance, depending upon the position of the follower 69 upon the bearing surface 74 of the pivoted arm 75. Thus, by turning the adjusting screw 71, the follower 69 may be moved along the surface 74 to a point directly above the cam follower 77 and thereby impart the full and complete action of the cam 78 to turn the trunnion 55 and move the grinding wheel 60 a relatively long distance towards and away from the regulating wheel; or the follower 50 69 may be moved along the surface 74 to a point directly above the center of the shaft 76 and thereby substantially negative the action of the cam 78; or the follower 69 may be moved along the surface 74 to an intermediate point so as to cause movement of the trunnion to move the grinding wheel towards and away from the regulating wheel a relatively short distance, or an amount satisfactory for finish grinding.

60 Preferably the cam 78 is so shaped and so positioned upon the shaft 79 as to impart an upward movement to the follower 69 to turn the trunnion 55 and move the grinding wheel 60 rapidly into approximate contact 65 with the work *w* and then relatively slowly

to grind the work to finished size and permit the grinding wheel to dwell and grind itself out.

In accordance with the provisions of the invention a precision grinding machine may be adjusted readily to cause either a relatively great or relatively small movement between the grinding wheel and the work being ground, depending upon whether it is desired to use the machine for rough or finish grinding. This may be accomplished readily without changing or removing any part of the mechanism.

The terms "regulating wheel" and "slowly rotated regulating wheel" are to be construed in the now commonly accepted understanding of those skilled in the centerless grinding art. The speeds of both the grinding wheel and the regulating wheel must necessarily be varied in accordance with the type and nature of the work to be ground as well as the particular operation to be performed. The grinding wheel is to be rotated at a speed found suitable for grinding the work and the regulating wheel is to be given such a speed that the work will rotate during the grinding operation at that rate which is found desirable for the particular operation to be performed. Without reference to the theory of operation, the regulating wheel serves to control the speed of the work and the work may be given a faster or slower speed by increasing or decreasing the speed of the regulating wheel respectively; by the speed of the work is meant the rate of rotation of the work.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

Having thus described my invention, what I claim as new and desire to secure by Letters Patent is:

1. A precision grinding machine comprising a rapidly rotated grinding wheel, means for holding work rotatively during grinding, power driven means for periodically moving the work and the grinding wheel relatively towards and away from each other through an invariable distance to grind the work to a predetermined size, and means for adjusting the extent of said relative movement.

2. A grinding machine comprising a rapidly rotated grinding wheel, a slowly rotated work regulating wheel, means for holding work in operative position between said wheels, and a cam controlled mechanism for moving one of the wheels towards and away from the other through an invariable distance including a trunnion for eccentrically mounting the movable wheel, and means for

changing the action of the cam effective for turning the trunnion to change the distance of travel of the movable wheel.

3. A grinding machine comprising a rapidly rotated grinding wheel and a slowly rotated work regulating wheel, means for holding work in operative position between said wheels, and a cam controlled mechanism for moving one of the wheels towards and away from the other an invariable distance including a trunnion for eccentrically mounting the movable wheel, a pivoted lever arranged to be actuated by the cam, and means responsive to the movement of any point on the lever for actuating the trunnion to move said wheel through either a long or a short distance.

4. A grinding machine comprising a slowly rotated work regulating wheel, means to hold work in position to be engaged and rotated thereby, a trunnion, a grinding wheel spindle eccentrically mounted therein for rotation, a grinding wheel on the spindle, a rotatably mounted cam, a pivoted lever operatively associated with the cam, and a follower adjustably mounted on the trunnion and adapted to engage the lever at any desired point so as to move the grinding wheel either a long or a short distance.

5. A grinding machine comprising a rapidly rotated grinding wheel, a slowly rotated work regulating wheel mounted below the grinding wheel, means for moving one of the wheels towards and away from the other an invariable distance, means for holding work in rotative contact with the regulating wheel and in position to be engaged by the grinding wheel, a rotatably mounted cam, and adjustable connections between said cam and movable wheel adapted to move the wheel towards and away from the other cyclically but through a variable and predetermined distance.

6. In grinding apparatus, in combination, a grinding throat adapted for simultaneous grinding and rotating action upon work of round section and including at least three members one of which members is in the form of a grinding wheel adapted to be rotated at relatively high speed, another of said members being in the form of a regulating wheel adapted to be rotated at a relatively low speed, and the third being a member for holding work of round section in operative relation to said two wheels, one of said members being movable to change the relation of the grinding throat to the work; means including an eccentric for moving said movable member; and mechanism adapted upon actuation to operate said eccentric, said mechanism including a controllable connection therebetween and said eccentric adapted to permit variation of the action of said eccentric in response to said mechanism.

7. In grinding apparatus, in combination,

a grinding throat adapted for simultaneous grinding and rotating action upon work of round section and including at least three members one of which members is in the form of a grinding wheel adapted to be rotated at relatively high speed, another of said members being in the form of a regulating wheel adapted to be rotated at a relatively low speed, and the third being a member for holding work of round section in operative relation to said two wheels, one of said members being movable to change the relation of the grinding throat to the work; means including an eccentric for moving said movable member; a lever; means for oscillating said lever; and means for connecting said eccentric to said lever, said connecting means being controllable to permit variation of the distance of the point of connection from the fulcrum of said lever.

8. In grinding apparatus, in combination, a grinding throat adapted for simultaneous grinding and rotating action upon work of round section and including at least three members one of which members is in the form of a grinding wheel adapted to be rotated at relatively high speed, another of said members being in the form of a regulating wheel adapted to be rotated at a relatively low speed, and the third being a member for holding work of round section in operative relation to said two wheels, one of said members being movable to change the relation of the grinding throat to the work; a pivoted lever adapted for oscillation about its pivot; and means forming a connection between said lever and said movable member for moving the latter; and means for varying at will the distance of the point of connection of said connecting means to said lever from the pivot of the latter.

9. In grinding apparatus, in combination, a grinding throat adapted for simultaneous grinding and rotating action upon work of round section and including at least three members one of which members is in the form of a grinding wheel adapted to be rotated at relatively high speed, another of said members being in the form of a regulating wheel adapted to be rotated at a relatively low speed, and the third being a member for holding work of round section in operative relation to said two wheels, one of said members being movable to change the relation of the grinding throat to the work; a pivoted lever; a cam for oscillating said lever about its pivot; and means operated by said lever for moving said movable member and having means whereby the effective arm of said lever may be changed.

10. In grinding apparatus, in combination, a grinding throat adapted for simultaneous grinding and rotating action upon work of round section and including at least three members one of which members is in the form

of a grinding wheel adapted to be rotated at relatively high speed, another of said members being in the form of a regulating wheel adapted to be rotated at a relatively low speed, and the third being a member for holding work of round section in operative relation to said two wheels, one of said members being movable to change the relation of the grinding throat to the work, a pair of levers 5 related to each other and having connecting means such that as the effective arm of one is lengthened the effective arm of the other is shortened; means responsive to movement of one of said levers for moving said movable member; and means for actuating the other lever.

11. In grinding apparatus, in combination, a grinding throat adapted for simultaneous grinding and rotating action upon work of 20 round section and including at least three members one of which members is in the form of a grinding wheel adapted to be rotated at relatively high speed, another of said members being in the form of a regulating wheel 25 adapted to be rotated at a relatively low speed, and the third being a member for holding work of round section in operative relation to said two wheels, one of said members being movable to change the relation of the 30 grinding throat to the work, a pair of levers related to each other and having connecting means such that as the effective arm of one is lengthened the effective arm of the other is shortened; means responsive to movement of 35 one of said levers for moving said movable member; and means for oscillating the other lever between predetermined limits.

12. In grinding apparatus, in combination, a grinding throat adapted for simultaneous 40 grinding and rotating action upon work of round section and including at least three members one of which members is in the form of a grinding wheel adapted to be rotated at relatively high speed, another of said 45 members being in the form of a regulating wheel adapted to be rotated at a relatively low speed, and the third being a member for holding work of round section in operative relation to said two wheels, one of said members 50 being movable to change the relation of the grinding throat to the work, a pair of levers related to each other and having connecting means such that as the effective arm of one is lengthened the effective arm of the 55 other is shortened; means responsive to movement of one of said levers for moving said movable member; and a cam for oscillating the other lever.

13. In grinding apparatus, in combination, 60 a grinding throat adapted for simultaneous grinding and rotating action upon work of round section and including at least three members one of which members is in the form of a grinding wheel adapted to be rotated 65 at relatively high speed, another of said

members being in the form of a regulating wheel adapted to be rotated at a relatively low speed, and the third being a member for holding work of round section in operative relation to said two wheels, one of said members being movable to change the relation of the 70 grinding throat to the work, a pair of levers related to each other and having connecting means such that as the effective arm of one is lengthened the effective arm of the 75 other is shortened; an eccentric responsive to the movement of one of said levers for moving said movable member; and means for actuating the other lever.

14. In grinding apparatus, in combination, 80 a grinding throat adapted for simultaneous grinding and rotating action upon work of round section and including at least three members one of which members is in the form of a grinding wheel adapted to be rotated at relatively high speed, another of said members being in the form of a regulating wheel adapted to be rotated at a relatively low speed, and the third being a member for holding work of round section in operative 85 relation to said two wheels, one of said members being movable to change the relation of the grinding throat to the work; a cam; means actuated by said cam and having portions moving throughout different distances; 90 and means for connecting said movable member selectively to any one of said portions of said actuated means.

Signed at Detroit, Michigan, this 30th day of January, 1926.
